Primary Examiner — Marianne Pandozzi(74) *Attorney, Agent, or Firm* — Florek & Endres PLLC(57) **CLAIM**

The ornamental design for a trivet, as shown and described.

DESCRIPTION

FIG. 1 is a perspective view of a trivet showing our new design;

FIG. 2 is a top plan view thereof;

FIG. 3 is a bottom plan view thereof;

FIG. 4 is a front view thereof;

FIG. 5 is a rear view thereof;

FIG. 6 is a right side view thereof;

FIG. 7 is a left side view thereof; and,

FIG. 8 is a top plan view thereof in an inverted, alternate configuration.

The broken lines in the drawings are included for the purpose of illustration and form no part of the claimed design.
